Primary Examiner — Nicole C Shiflet*Assistant Examiner* — Karen M. Jones(74) *Attorney, Agent, or Firm* — NKL Law; Jae Youn Kim**CLAIM**

I claim the ornamental design for an electronic cigarette, as shown and described.

DESCRIPTION

FIG. 1 is a perspective view of an electronic cigarette showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dash-dash broken lines in the drawings show portions of the electronic cigarette that form no part of the claimed design.
